DAVID E. DUFRESNE, OF ST. LAMBERT, AND WILLIAM ADAMSON, OF MAISONNEUVE,
QUEBEC, CANADA.

BEEF-FATTING TABLE.

1,314,579.

Specification of Letters Patent. Patented Sept. 2, 1919.

Application filed March 8, 1919. Serial No. 281,491.

To all whom it may concern:

Be it known that we, DAVID E. DUFRESNE and WILLIAM ADAMSON, both subjects of the King of Great Britain, residing at St. 5 Lambert and Maisonneuve, respectively, Province of Quebec, Canada, have invented certain new and useful Improvements in Beef-Fatting Tables; and we do hereby declare that the following is a full, clear, and 10 exact description of the invention, such as will enable others skilled in the art to which it appertains to make and use the same.

The present invention relates to apparatuses used in abattoir houses or the like and 15 more particularly to an apparatus for gathering and collecting fats from slaughtered animals.

An object of the present invention is to provide working tables to be used in connection with abattoirs wherein a proper 20 commercial and sanitary disposal of the waste material is permitted so that fats which are severed from the various parts of the slaughtered animal may be easily and 25 readily gathered.

With the above and other objects in view which will hereinafter appear as the description continues, the invention consists of the novel features of construction, combination 30 and formation of parts as will be hereinafter more fully described and particularly pointed out in the appended claims.

In the accompanying drawings has been shown a simple and preferred form of the 35 invention, it being, however, understood that no limitation is necessarily made to the precise structural details herein exhibited, but the right is hereby reserved to any changes, alterations or modifications to which re- 40 course may be had that come within the scope of the claims without departing from the spirit of the invention or sacrificing the efficiency of the same.

In the accompanying drawings: 45 Figure 1 is a perspective view of the tables embodying the present invention;

Fig. 2 is a detail cross section through the same;

Fig. 3 is a vertical transverse section 50 through one of the tables;

Fig. 4 is a detail perspective view of one of the drainage pipes;

Fig. 5 is a detail perspective view of one 55 of the drainage pipes used in connection with the punch fattening table;

Fig. 6 is a sectional elevation of the punch table.

Referring now more particularly to the accompanying drawings wherein like and corresponding parts are designated by similar reference characters throughout the several views,

The fattening tables embodying the present invention as herein shown comprise three separate tables, one of which indicated by 65 the numeral 1 is called the punch fattening table, the one indicated by the numeral 2 being the running fattening table, and the table indicated by the numeral 3 is termed the main fattening table. The parts of a slaughtered animal which are to have the fats severed therefrom are placed upon these various tables wherein the operators may cut the fat from the beef and this fat will be finally 70 collected in a sanitary manner to prevent 75 any wastage.

The punch table indicated by the numeral 1 comprises the supporting legs 4 holding a top plate 5. This top plate 5 comprises two inclined sections 6 which have their 80 highest points terminating adjacent the medial portion of the table and their lower edges communicating with the side troughs 7 and these troughs 7 may have suitable drainage pipes leading therefrom. Adapted 85 to be seated within these troughs or gutters 7 are the plates 8 which are adapted to terminate flush with the lower edge of the sections 6. These plates are preferably of an inverted U-shaped cross section so that they 90 may rest within the gutters, but their upper walls are provided with a plurality of elongated openings 9. The operators are adapted to stand on each side of this table, and when the stomach portion of a slaughtered 95 animal is placed thereupon the stomach may be opened and the waste material removed therefrom. Any undigested food such as long pieces of straw contained within the stomach is scraped therefrom and these 100 pieces of food will fall through the openings 9. As the sections 6 of the table are inclined the waste material will be drained toward the trough, thereby keeping the top of this table clean and sanitary at all times.

The 105 fats severed from the stomach portion of the animal are then placed upon the running table 2. This running table 2 comprises the supporting legs 10 having an incline top 11, and encircling the three sides of this top are 110

the flanges 12 which keep the fat upon this top 11 and prevent the same from dropping upon the floor. Communicating with the lower end of this inclined top 11 and arranged at one side of the table is a drainage trough or gutter 13 and adapted to be seated within this gutter 13 is a perforated plate 14. A drain pipe 15 leads from this gutter and communicates with a suitable sewer drainage so that the waste matter and water may be carried from the top 11. Arranged above this top 11 are the spray nozzles 16 and these nozzles have hot and cold water pipe connections 17 communicating therewith so that hot water or cold when it is desired may be applied to the fats and intestines accumulated upon this table. The intestines containing fat of the animal are placed upon this table 11 and the waste material contained within the intestines is withdrawn therefrom and deposited within the pockets 18 by the operators. These pockets 18 have suitable drainage pipes 19 leading therefrom which communicate with the drainage pipe 15. The fat contained upon the table 1 falls by gravity upon the plate 14 where all the water and other liquids contained upon the fat will be drained thereupon and finally the fat is pushed along this plate 14 by the operators until it reaches the table 3. Before cutting the fat from the intestines it is desirable to raise their temperature to about ninety degrees so as to make better working conditions. The hot water from the nozzle 16 will flow over the intestines contained upon this table 2, thereby increasing their temperature and finally the intestines after having their temperature raised and thoroughly cleaned are placed upon the hook rack 20 supported upon the table 3 so that operators standing in front of this table 3 may cut the fat from the intestines. This table 3 comprises the supporting legs 21 having mounted thereupon an inclined rear wall 22 upon which is supported the rack bar 20 and also supported upon this table is an inclined front wall 23 and these walls 22 and 23 have their lower ends terminating adjacent each other so as to provide a fat collecting trough 23'. This table 3 is provided with a gutter or trough 24 which communicates with the trough 13 and has seated therein a perforated plate 14. The perforations within these plates 14 are so proportioned that the water and other liquids contained thereupon may drain from the fats, but the fats will not pass through these perforations, thereby providing a suitable drainage for the fats and preventing any other loss thereof. The fat severed from the intestines and contained upon the plates 14 is forced by the operators between the walls 22 and 23 and finally it is moved into a suitable receiving tray 25. This tray 25 has arranged therein a perforated plate

26 which supports the fat but permits the water to drain from the fat and this water is permitted to pass within an outlet pipe 27 which pipe is connected to a suitable sewerage system. When the fat has passed within the table 3 it is desirous to cool its temperature so that all of the fat may be readily collected. Arranged at the upper end of the rear wall 22 of this table is a perforated pipe 28 and arranged at the upper end of the inclined wall 23 is a similar perforated pipe 29. These pipes communicate with a suitable cold water supply and this cold water is permitted to drain down the inclined walls 22 and 23 so as to lower the temperature of the fat contained within the table 3. A perforated pipe 30 may be arranged above the plate 14 of this table 3 so that hot water may be supplied to the troughs 24 and 13, whereby the gutter may be cleaned. Arranged above this table 3 is a nozzle 31 having communicated thereto the cold and hot water supply pipes 32 whereby hot water may be supplied to this table 3 when it is desired to clean the same. 90

From the foregoing it is obvious that we have provided beef fatting tables in which the intestines of a slaughtered animal may be properly handled in a sanitary manner and that the fat severed from said intestines may 95 be easily and readily gathered.

Having thus fully described our invention, what we claim as new and desire to secure by Letters Patent is:

1. The combination with a table having 100 an inclined top, of a trough formed with and extending along one side of said top, an inverted U-shaped plate adapted to be seated within said trough and the top of said plate lying flush with the top of said table and 105 having elongated openings therein.

2. A beef fatting table comprising a top plate, a trough formed with said top plate and extending along one side thereof, and a detachable perforated plate adapted to rest 110 within said trough for covering the same, substantially as and for the purpose specified.

3. In an apparatus of the character described comprising a table having a top 115 plate, said top plate comprising two inclined sections, a trough formed at the intersection of the lower ends of said sections, a trough disposed adjacent the upper end of one of said sections, a trough plate arranged within 120 said last mentioned trough and said trough plate having elongated openings therein.

4. In an apparatus of the character described comprising a table consisting of angularly disposed walls, a trough formed by 125 the intersecting ends of said walls, a trough connected to the top of one of said walls, a perforated plate arranged within said trough arranged at the top of one of said walls, a rack arranged adjacent the top of 130

the other wall and water spraying pipes disposed adjacent the upper ends of said walls.

5. In a device of the character described comprising a table consisting of a top having inclined walls converging toward their lower ends, a trough arranged adjacent the upper ends of one of said walls, a perforated plate arranged within said trough, a rack

supported upon one of said walls, and cold water spraying pipes arranged adjacent the 10 upper ends of said walls substantially as and for the purpose specified.

In witness whereof we have hereunto set our hands.

DAVID E. DUFRESNE.
WILLIAM ADAMSON.
